UNITED STATES PATENT OFFICE.

HYMAN MAIMIN, OF NEW YORK, N. Y., AND WILLIAM J. MARSHALL, OF NEWARK, NEW JERSEY, ASSIGNORS TO H. MAIMIN CO., INC., A CORPORATION OF NEW YORK.

SHARPENING APPARATUS FOR CLOTH-CUTTING-MACHINE KNIVES.

1,303,936.

Specification of Letters Patent.

Patented May 20, 1919.

Application filed March 22, 1917. Serial No. 156,686.

To all whom it may concern:

Be it known that we, HYMAN MAIMIN and WILLIAM J. MARSHALL, both citizens of the United States, said MAIMIN residing in 5 the city, county, and State of New York and said MARSHALL residing in Newark, county of Essex, and State of New Jersey, have invented certain new and useful Improvements in Sharpening Apparatus for 10 Cloth-Cutting-Machine Knives; and we do hereby declare the following to be a full, clear, and exact description of the invention, such as will enable others skilled in the art to which it appertains to make and 15 use the same.

This invention relates to sharpening means for the knives of cloth cutting machines of the reciprocating-knife type, and has for its object to provide an apparatus 20 to permit rapid and correct sharpening of the knife and particularly of the chopping edge thereof, when the knife is removed from the cloth cutting machine for any reason.

25 In sharpening the chopping edge of a knife of the kind described, it has always been found very difficult to properly incline the knife relative to the sharpening stone, and where either the knife or the 30 stone is manually held the sharpening operation is tedious and of indefinite duration, the new edge is seldom uniform, and the result is generally unsatisfactory.

In accordance with the present invention, 35 there is provided a sharpening means for the chopping edge of the knife and a knife-holder into which the knife may readily be placed and wherein it may be held in fixed and proper relation to the knife sharpening 40 means during the sharpening operation. Preferably the holder is so constructed as to take knives of different sizes and has means for adjustably positioning the chopping edge of the knife so that this edge may 45 be treated by the sharpening stones in a manner best suited to the particular work for which the knife is to be used.

The sharpening means employed consists 50 essentially of a pair of sharpening stones so mounted that they may be caused to wipe alternately across the chopping edge of the knife when the knife is clamped in the holder. The particular mechanism for operating the stones here shown is constructed 55 in accordance with the invention disclosed

and claimed in a co-pending application Serial No. 161,196 filed April 11, 1917, by one Henry B. Batjer, and this actuating mechanism does not in itself form any part of the present invention. We have found that 60 the best results are attained if the knife blade is so supported that its lower chopping edge is projected freely into the field of operation of the stones, so that it may be said to float in this field of operation, the 65 blade being sufficiently flexible to permit its lower end to be deflected somewhat by the stones. The shank of the knife should be grasped firmly by the holder. Furthermore, the arrangement should be such that the 70 blade may be more or less projected so that the stones may be made to act upon the edge either to form a sharp cutting corner or a rounded corner where the lower chopping edge of the knife meets the forward 75 slicing edge.

The invention will be more clearly understood from the following description, when taken in connection with the accompanying drawings illustrating the invention 80 in its preferred forms.

In these drawings Figure 1 is a side elevation of an embodiment of the invention; Fig. 2 is a front elevation thereof; Fig. 3 is a view partly in elevation and partly in 85 section showing another embodiment; Fig. 4 is a view of the same embodiment taken at right angles to Fig. 3 and Fig. 5 is a section on line 5-5 of Fig. 3.

In the embodiment illustrated in Figs. 1 90 and 2 a base 6 has a bracket 7 for supporting the knife sharpening means, and a standard 8 constituting a knife-holder, these two parts being in fixed relation to one another. The sharpening device 9 is of the 95 type in which a handle such as the handle 9^a is turned to bring two sharpening stones 9^b alternately into sliding engagement with the opposite sides of the chopping edge of the knife properly positioned in the knife-holder, as illustrated in Fig. 1. A knife sharpening attachment of this general type is shown, for example, in Patent No. 1,186,488 issued to Hyman Maimin on June 6, 1916. The particular form of the sharpening device here shown is a modification, in accordance with the disclosure of the above-mentioned application of Henry B. Batjer.

The standard 8 is vertically slotted as in- 110

dicated at 10, within which slot the knife 12 is adapted to be inserted, the standard being reduced in width and cut away as shown to provide upper and lower pairs of ears 8^a and 8^b. One of the ears 8^a has a boss 11 through which a knurled clamp-screw 13 is threaded, a knurled jam-nut 14 being threaded on the clamp-screw. A thumb-screw 15 is threaded up into the two ears 8^b 10 so that the upper end of the screw may support the lower end of the knife. The screw 15 constitutes a vertically adjustable shelf upon which the edge 12^a of the knife is adapted to rest when the knife is inserted in 15 the slot 10 and clamped therein by means of the clamp-screw 13. This edge 12^a of the knife is a blunt portion thereof which is never sharpened and is shielded from engagement with the fabric being cut by the 20 knife guiding channel in the knife standard of the cloth cutting machine. The chopping edge 12^b of the knife extends between this section 12^a and the straight slicing edge 12^c. The ears 8^b are so formed that the entire 25 chopping edge 12^b and the lower portion of the slicing edge 12^c are exposed, when the lower end of the knife is supported on the upper end of the screw 15 to position the knife properly relative to the field of 30 operation of the sharpening device 9. The ears 8^b are shaped as indicated at 8^b, to permit wiping strokes of the stones 9^b toward and away from the plane of the knife blade and of maximum efficiency. The portion 35 of the slot 10 which is located between the ears 8^b is of greater width than the thickness of the knife, as shown clearly in the drawing, to project the chopping edge of the knife freely into the field of operation 40 of the device 9 where it floats so that its lower edge may be deflected somewhat by the stones as they are wiped against the knife.

When the knife is to be mounted in the 45 apparatus and sharpened, the knife is first arranged in place relative to the sharpening device 9, by inserting the knife blade in the slot 10, as indicated, to rest the blunt portion 12^a of the knife on the upper end of the screw 15. Should further adjustment of the 50 knife then be necessary, such adjustment may be had by turning the screw 15 as required. When the knife is seated properly in the slot 10 and on the screw 15, the clamp-screw 13 is tightened to rigidly hold the 55 knife during the sharpening operation in the precise adjustment obtained as just described. It has been found that by this means the knife may be readily adjusted for 60 sharpening, and also to arrange the chopping edge 12^b thereof at the required angle to the paths of movement of the stones 9^a either for shaping the chopping edge as indicated by the full line or as indicated by 65 the dot and dash line of Fig. 1, while

sharpening such edge. The rounded corner indicated by the dot and dash line is the edge-formation which the knife should have when used for cutting plush goods, the sharp corner indicated by the dotted line being generally used when cutting other fabrics. 70

As is well known, the knives of cloth cutting machines are commonly provided in a plurality of different lengths. In the apparatus of Figs. 1 and 2, the clamp screw 75 14 engages and holds an intermediate portion of the knife 12 which is spaced from the lower end of the knife the correct distance to properly position the chopping edge of the knife relative to the sharpening device. The apparatus of Figs. 1 and 2 is thus adapted to receive and sharpen knives of varying lengths without any necessity for displacing the field of operation of the clamp screw 14 relative to the field of operation 80 of the sharpening device. 85

Referring to Figs. 3, 4 and 5, a support 19 carries a bracket 20 and a tubular standard 21 spaced a fixed distance from the bracket, the bracket supporting a sharpening device 90 22 similar to the sharpening device 9 of Fig. 1.

The standard 21 has a shelf 23 extended toward the sharpening device 22 and arranged slightly below the field of operation 95 of the sharpening stones thereof. The shelf 23 is provided with a groove 24 for receiving the blunt portion 12^a of the knife 12. A vertical bar 25 is movable up and down in the standard 21, and there is provided a set-screw 26 for securing the bar 25 in any desired position of adjustment. The bar 25 is vertically slotted as indicated at 28, the slot 28 being in line with a slot 29 through the tubular standard 21 and with the groove 24 100 in shelf 23. A knurled pivot-screw 30 is threaded in the bar 25, the shank of the screw forming a pintle passing across the slot 28, so that it may lie within the fork 105 usually found at the upper end of a knife of the character here referred to. Two knurled adjusting screws 31 are threaded in the bar 25 for engaging the rear edge 12^a of the knife, one above the axis of the pivot screw 30 and the other below such axis. 110

The construction just described, while more complicated than that of Fig. 1, has the advantage that the apparatus may be readily adjusted and held by the set screw 26 to position the pivot screw 30 so that the latter, 115 by engaging with the forked upper end of the knife 12, provides a fixed center about which the knife may be swung to position it properly to present one or another portion of its edge to the stones of the sharpening 120 device. This position having been roughly arrived at the knife is closely adjusted and fixed by manipulation of the fulcrum screws 31.

It will be seen that this apparatus pro- 130

- vides a knife-holder adapted to receive a knife of any commercial length and permitting the easy adjustment of the knife to a fixed position with relation to the plane of the action of the sharpening stones, this position being in general such that the longitudinal axis of the knife is substantially tangent to the path of the stones at the point where they make sharpening engagement with the lower edge of the knife. It is then only necessary to rotate the handle 9^a to impart to the knife a correctly sharpened edge. The conditions incident to the sharpening of the edge are thus substantially predetermined by the manufacturer of the apparatus and are not left to the individual judgment of the user; with the single exception that provision is intentionally made for adjusting the knife so that different portions of the edge may be presented to the predetermined action of the sharpening stones, in accordance with the particular work for which the knife is to be used.
- What we claim is:
1. In a device for sharpening the chopping edge at the end of a long straight knife for cloth cutting machines by means of sharpening stones adapted to move alternately over a curved path, the combination of a standard, and means for engaging and holding an intermediate portion of the knife at a point spaced from the lower end of the knife the proper distance to position the chopping edge relative to the sharpening device.
2. An apparatus of the kind described having a knife-sharpener and a support therefor and a knife-holder adapted to hold the knife with its blade clamped in the holder and its lower edge floating in the field of operation of the sharpener, said sharpener including a pair of sharpening stones, a mechanism for wiping them with sharpening pressure alternately across opposite sides of the knife edge to be sharpened and means for adjusting the knife in the holder to present one or another portion of its edge in sharpening relation to the said stones.
3. An apparatus for sharpening the chopping-edge at the end of a straight knife for cloth cutting machines, comprising a knife-sharpener and a knife-holder adapted to hold the blade of the knife with its said edge exposed in a predetermined relation to the sharpener, the knife-holder comprising a device for supporting the lower end of the knife and a device for clamping the knife to the holder as thus supported.
4. An apparatus of the kind described comprising a base, a knife-holder positioned thereon and having a shelf to support the lower end of the knife and an uprising stand-
- ard adapted to clamp the blade of the knife and hold it with its lower edge substantially free, and a knife-sharpener supported in fixed relation to the knife-holder, whereby a knife fixed in the holder has the edge to be sharpened presented in predetermined relation to the knife-sharpener.
5. An apparatus of the kind described comprising a base, a knife-holder positioned thereon and having a shelf to support the lower end of the knife and an uprising standard adapted to clamp the blade of the knife and hold it with its bottom chopping edge substantially free, and a knife-sharpener supported in fixed relation to the knife-holder, whereby a knife fixed in the holder has its edge presented in predetermined relation to the knife-sharpener, and a set screw for adjusting the knife in the holder to present one or another portion of its edge in like predetermined relation to the sharpener.
6. An apparatus for sharpening the chopping-edge at the end of a straight knife for cloth cutting machines, comprising a knife-sharpener and a knife-holder adapted to hold the blade of the knife with its said edge exposed in a predetermined relation to the sharpener, the knife-holder comprising a device for supporting the lower end of the knife and a device for clamping the knife to the holder as thus supported, one of said devices being vertically adjustable relative to the other.
7. An apparatus of the kind described comprising a knife-holder having a clamp with a transverse pintle adapted to receive a notch at the upper end of the knife, and a shelf upon which the lower end of the knife is adapted to rest, the clamp being vertically adjustable with respect to the shelf to adapt the holder to knives of different lengths, and a knife-sharpener supported in predetermined relation to the holder.
8. An apparatus of the kind described comprising a knife-holder having a clamp with a transverse pintle adapted to receive a notch at the upper end of the knife and a shelf upon which the lower end of the knife is adapted to rest, the clamp being vertically adjustable with respect to the shelf to adapt the holder to knives of different lengths, a knife-sharpener supported in predetermined relation to the holder, and a pair of set screws positioned one above and the other below the pintle for adjusting the position of the knife in the holder to present one or another portion of its lower edge in sharpening relation to the knife-sharpener.

In testimony whereof, we affix our signatures.

HYMAN MAIMIN.
WILLIAM J. MARSHALL.
